UNITED STATES PATENT OFFICE.

SIMON C. COLLINS, OF BAINBRIDGE, PENNSYLVANIA.

RAIL-FASTENER.

1,200,468.

Specification of Letters Patent. Patented Oct. 10, 1916.

Application filed February 18, 1916. Serial No. 79,208.

To all whom it may concern:

Be it known that I, SIMON C. COLLINS, a citizen of the United States, residing at Bainbridge, in the county of Lancaster and State of Pennsylvania, have invented a new and useful Rail-Fastener, of which the following is a specification.

This invention relates to rail fasteners, one of its objects being to provide novel means whereby the fish plate and the base plate will be held properly assembled relative to each other and to the rails, it being possible to disconnect the parts from the rails without shifting said rails out of alignment.

A further object is to provide a fastener which does not require the use of bolts or like fastening means in order to hold it in proper relation to the rails.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings, Figure 1 is a plan view of a rail joint embodying the present improvements. Fig. 2 is a bottom plan view.

Fig. 3 is a section on line A—B Fig. 1. Fig. 4 is a section on line C—D Fig. 3, the ribs on the base plate being shown in plan. Fig. 5 is an enlarged section on line E—F Fig. 4. Fig. 6 is a side elevation of a portion of one of the fish plates, a portion of the base plate, and the projecting end portion of one of the wedging keys.

Referring to the figures by characters of reference R designates the rails to be connected, these rails projecting between opposed fish plates 1 and 2 each of which has an upstanding web engaging portion 3, a base engaging portion 4 and spaced depending flanges 5. The inner ends of these flanges are notched or recessed, as at 6. The

fish plate 2 is provided at the lower edge of its web engaging portion with an outstanding longitudinal lip or bead 7 forming a recess 8 thereunder for the purpose hereinafter set forth. A longitudinal bead 9 may 55 also be provided along the side of the base engaging portion of said fish plate.

A flat base plate 10 is adapted to extend under the meeting end portions of the rails R and is provided, adjacent its ends, with 60 upstanding retaining ribs 11 and 12 while formed within the base plate beyond these ribs are openings 13 for the reception of spikes 14 or other suitable fastening devices. Formed in each side of the base plate 10 is 65 an elongated recess 15 and a short recess 16. Thus there is provided an ear 17 between each recess 15 and the adjacent recess 16. The length of the recesses 15 is somewhat less than the distance between the flanges 5 70 at the two sides of the rails and it will thus be seen that when the ears 17 are seated within the notches or recesses 6, as shown in Fig. 4, the outer end walls of the recesses 15 will be seated within the adjacent recesses 75 6 so that the plate 10 will thus be supported by the bottom walls of the recesses 6. When plate 10 is positioned in this manner relative to the recesses 6 the ribs 11 and 12 are arranged beyond the sides of the fish plates, 80 rib 11 abutting against the fish plate 1 as shown in Fig. 3, while a key receiving space is formed between the rib 12 and the fish plate 2.

A wedge-shaped retaining strip 18 is 85 adapted to be inserted between the rib 12 and the fish plate 2, this strip being provided with a longitudinal groove 19 for the reception of the rib 9. Furthermore a tongue 20 extends upwardly and inwardly 90 from the strip 18 and is adapted to project into the recess or groove 8 formed under the rib or bead 7. A wedge-shaped key 21 is 95 insertible longitudinally between the strip 18 and the rib 12 and has a notch 22 in that face thereof engaging the strip 18, this notch being adapted to register with any one of a series of notches 23 formed in the strip 18. A spike 24 is adapted to be driven into the registering notches, the lower end of the 100

spike being designed to come against the beveled wall 25 at the inner end of one of the notches 16 so as thus to be deflected or bent as shown particularly in Fig. 5 and consequently be held against withdrawal from the joint.

For the purpose of holding the rails against longitudinal displacement relative to the fastening means, each rail is provided 10 upon its bottom face and close to the plate 10, with an extension or enlargement 26 adapted to extend close to the plate 10, these extensions being provided with projecting portions 27 extending into the recesses 15. 15 These projecting portions, by engaging the sides of the plate 10 serve to hold the rails R against longitudinal movement toward the plate and also permit the necessary sliding movement of the plate 10 transversely 20 of the rails in order to bring the recesses 16 into register with the recesses 6, thus to permit disengagement of the plate 10 from the flanges 5.

It will be apparent that the parts can be 25 tightened readily by driving the key 21 longitudinally and can then be held by driving a spike 24 into the registering notches 22 and 23. When it is desired to detach the parts, spike 24 is withdrawn, the wedging 30 key 21 and strip 18 are removed and plate 10 is then shifted transversely under the rails until the notches 16 are brought into the recesses 6 and the outer walls of the recesses 15 are removed from the adjacent 35 notches 6. When the parts are thus positioned the plate 10 can be lowered out of engagement with the flanges 5.

In order to limit the longitudinal movement of the strip 18, a nose 18' is preferably 40 extended downwardly from one end thereof and is designed to lap one side of the base plate 10.

What is claimed is:—

1. A rail fastener including opposed fish 45 plates each having spaced depending flanges at its outer side, the inner ends of the flanges being recessed, a base plate extending between said spaced flanges and having upstanding retaining ribs, one of said ribs 50 being engaged by one of the fish plates, wedging means interposed between the other fish plate and the adjacent upstanding rib for holding the base plate with its recesses removed from the recesses in the depending 55 flanges, said base plate, when relieved from the holding action of the wedging means, being shiftable longitudinally to bring its recesses within the recesses in the depending flanges.

60 2. A rail fastener including opposed fish plates, base flanges depending from each fish plate, the inner ends of the flanges being recessed, a base plate normally seated in the recesses and having recesses in its

sides shiftable to position between the depending flanges to release said base plate from the flanges, upstanding ribs upon the base plate, one of said ribs being normally engaged by one of the fish plates, wedging means insertible between the other fish plate and the other upstanding rib to hold the base plate against movement to released position, and means for holding said wedging means against displacement.

3. A rail fastener including opposed fish 75 plates, base flanges depending from each fish plate, the inner ends of the flanges being recessed, a base plate normally seated in the recesses and having recesses in its sides shiftable to position between the depending flanges to release said base plate from the flanges, upstanding ribs upon the base plate, one of said ribs being normally engaged by one of the fish plates, wedging means insertible between the other fish plate 80 and the other upstanding rib to hold the base plate against movement to released position, a tongue extending from the wedging means and insertible into one of the fish plates, and means for fastening together the wedging 85 means.

4. Rail fastening means including opposed fish plates, spaced flanges depending from each fish plate and having recesses in their inner ends, a base plate insertible under the fish plates and between the flanges, the side edges of the base plate being normally seated in the recesses, said base plate having side recesses for releasing the base plate from the flanges when said base plate is shifted 95 longitudinally in one direction, upstanding ribs upon the base plate, one of said ribs engaging one of the fish plates, a wedging strip interposed between the other fish plate and rib, a tongue upon said strip and projecting into the adjacent fish plate, a wedging key interposed between the wedging strip and the adjacent rib, and means for fastening together the key and the wedging strip.

5. Rail fastening means including opposed fish plates, spaced flanges depending from each fish plate and having recesses in their inner ends, a base plate insertible under the fish plates and between the flanges, the side edges of the base plate being normally seated in the recesses, said base plate having side recesses for releasing the base plate from the flanges when said base plate is shifted longitudinally in one direction, upstanding ribs upon the base plate, one of said ribs engaging one of the fish plates, a wedging strip interposed between the other fish plate and rib, a tongue upon said strip and projecting into the adjacent fish plate, a wedging key interposed between the wedging strip and the adjacent rib, means for fastening together the key and the wedging

strip, rails extending between the fish plates and resting on the base plate, and projections upon the lower faces of the rails and at opposite sides of the base plate, each projection having an extension seated in one of the side recesses in the base plate.

5 In testimony that I claim the foregoing

as my own, I have hereto affixed my signature in the presence of two witnesses.
